UNITED STATES PATENT OFFICE.

CHARLES F. SCHOLLE, OF NEW YORK, N. Y., ASSIGNOR TO ELMS & SELLON, OF NEW YORK, N. Y.

DESIGN FOR TEXTILE FABRIC OR SIMILAR ARTICLE.

51,242.

Specification for Design.

Patented Sept. 4, 1917.

Application filed June 22, 1917. Serial No. 176,429. Term of patent 7 years.

To all whom it may concern:

Be it known that I, CHARLES F. SCHOLLE, a citizen of the United States, residing in the city of New York and State of New York, have invented a new, original, and ornamental Design for Textile Fabric or Similar Article, of which the following is a specification in such terms as will enable any one skilled in the art to which it appertains to make and use the same, reference being had to the accompanying drawings, forming part thereof.

The figure of the drawing is a plan view of a portion of a textile fabric illustrating my new design.

The design is intended to be repeated or matched out upon either side indefinitely, as is usual in such cases; a portion of the repeat being shown outside the dotted lines a, and b.

What I claim is:—

The ornamental design for textile fabric or similar article as shown and described.

CHAS. F. SCHOLLE.
